APPARATUS FOR SPINNING RAYON

Wilhelm Wuppermann, Berlin-Zehlendorf,
GermanyApplication November 9, 1937, Serial No. 173,691
In Germany May 15, 1937

12 Claims. (Cl. 18—8)

My invention relates to improvements in apparatus for spinning rayon, and more particularly in apparatus of the type comprising a rotary tubular container adapted to have the coagulating bath circulated therethrough, and a nozzle for the spinning liquid such as viscose fixed within said container and rotatable therewith, the spinning liquid or viscose delivered from the nozzle in the form of filaments being coagulated within the said container and twisted when it leaves the said container. One of the objects of the improvements is to provide an apparatus of this type which is simple in construction and reliable in operation, and with this object in view my invention consists in constructing the said tubular container in the form of a centrifugal pump adapted to draw the coagulating liquid through the said container, the said container being immersed with its open bottom and into a suitable coagulating liquid. Another object of the improvements is to provide an apparatus in which air or gas which may get into or developed within the coagulating liquid flowing through the said container is removed at the top end of the container, and with this object in view my invention consists in constructing the container at its top end so that the said gas or air is delivered together with the coagulating liquid.

For the purpose of explaining the invention several examples embodying the same have been shown in the accompanying drawings in which the same reference characters have been used in all the views to indicate corresponding parts.

In said drawings:

Fig. 1 is a sectional elevation showing a spinning apparatus in which the nozzle is located at the bottom of the rotary container, and the spinning liquid or viscose passes through the said container in upward direction.

Fig. 2 is a similar sectional elevation showing a modification in which the nozzle is located near the top part of the container, the spinning liquid or viscose and the filament being formed moving through the said container in downward direction.

Fig. 3 is a sectional plan view taken on the line 3—3 of Fig. 2.

Fig. 4 is a sectional elevation viewed from the right in Fig. 2.

Figs. 5 and 6 are similar elevations showing the parts of the spinning apparatus in different positions.

Fig. 7 is a fragmentary sectional elevation showing a modification.

Fig. 8 is a sectional plan view taken on the line 8—8 of Fig. 7.

Fig. 9 is a detail sectional elevation taken on the line 9—9 of Fig. 7.

Fig. 10 is a fragmentary sectional elevation showing another modification of the spinning apparatus.

Fig. 11 is a sectional plan view taken on the line 11—11 of Fig. 10.

Fig. 12 is a fragmentary sectional plan view taken on the line 12—12 of Fig. 10.

Fig. 13 is a detail sectional elevation showing another modification.

Fig. 14 is a fragmentary sectional elevation showing another modification.

Figs. 15, 16 and 17 are detail sectional elevations showing other modifications of the spinning nozzle, and

Figs. 18 and 19 show another modification.

20 In the example shown in Fig. 1 the spinning apparatus comprises a vertically mounted rotary pipe 1 carrying a spinning nozzle 2 at its top and passed through the bottom of a receptacle 3 containing a suitable coagulating bath, the said pipe being adapted to be rapidly rotated. To the pipe

25 1 a pipe 4 of larger diameter is fixed which is immersed with its open bottom end into the coagulating bath contained within the receptacle 3, and which is formed at its top end with in-

30 clined delivery openings 5. On the pipe 4 a cup 6 is removably mounted, and to the said cup a tubular container 7 is fixed. The cup 6 encloses the nozzle 2. At its top end the container 7 flares outwardly at 8, and it is closed by a conical

35 lid 9 formed at its center with a delivery opening for the thread 10 being formed. Around the outer upper margin of the flaring part 8 of the container there are delivery openings 11 for the coagulating bath. The diameter of the central

40 opening made in the lid 9 is not larger than is necessary for passing the filament 10 and a part of the coagulating bath therethrough. It will be seen that the pipe 4, the cup 6, the container 7, and the lid 9 together constitute a rotary con-

45 tainer, arranged in vertical position, whose otherwise continuous walls have a lower intake adjacent the axis of rotation, and an upper delivery more remote from the axis of rotation than the intake.

50 The apparatus is operated as follows:

When the apparatus is arranged and is in the condition shown in Fig. 1, the lower end of the pipe 4 extending beneath the surface of a bath 3 of coagulating liquid, and with the understanding that the entire container, including the parts

4, 6, 7, 8, and 9, is filled with liquid, the rapid rotation of this container will cause coagulating liquid to be drawn upwardly from the receptacle 3 and to be ejected through the openings 11. The rotating container thus acts as a centrifugal pump. Within the pipe 4 rotary movement is imparted to the coagulating liquid, so that the said liquid delivered through the passages 5 into the cup 6 and flowing past the nozzle 2 has no rotary movement relatively to the said rotating nozzle. The spinning liquid such as viscose delivered from the nozzle 2 moves in the direction of the upwardly flowing coagulating liquid, and the filament being formed is not twisted before it is delivered through the central hole made in the lid 9, and it is twisted while it moves from the said hole to a collecting device.

Any air or gas which might be developed within the container 7 is carried upwardly with the coagulating liquid and delivered therewith through the openings 11, such gas delivery being assisted by the conical shape of the lid 9.

In Fig. 2 I have shown a modification in which the nozzle 13 is located near the top end of the rotary container 16 for the coagulating bath.

As shown, the spinning apparatus comprises a pipe 14 for the supply of the spinning liquid or viscose, a spinning head 15 carrying the nozzle 13 and fixed to the pipe 14, a container 16 in the form of a funnel immersed with its bottom end into a suitable coagulating bath, a three-phase motor 17 for imparting rotary movement to the spinning head, and a frame 18, 19 carrying the spinning apparatus and mounted for being vertically shifted between rails 20 and 21. The frame 18, 19 is suspended by means of a rope or chain 24. Thus the spinning apparatus is adapted to be moved upwardly and downwardly between the rails 20, 21 for more or less immersing the container 16 to desired depth in the coagulating bath. The head 15 is provided peripherally with bores 26 that in the assembly constitute the delivery of the centrifugal pump whose barrel is the container 16 operating in like manner as the container of Fig. 1 already described.

In the normal operation of the apparatus the container 16 is immersed into the coagulating bath with its bottom end only, and the coagulating bath is drawn upwardly by means of bores 26 provided at the top end of the container and acting as a centrifugal pump. A jacket 27 disposed around the container 16 and immersed into the coagulating bath is provided with ribs 28 preventing the transmission of the rotary movement of the container 16 to the coagulating bath. These ribs 28 are in the ensuing claims characterized as braking members.

The coagulating liquid ejected from the centrifugal pump 26 is collected within a receptacle 29 from which it is delivered through a gutter 30 to a receptacle in which it is regenerated before it is returned to the receptacle 31 containing the coagulating bath.

In the operation of the apparatus air may get into the container, or gas may be developed by the action of the coagulating liquid on the viscose, and means are provided for removing such air and gas from the top part of the container. These means are shown in detail in Figs. 7, 8 and 9. Below the top end of the container 16 one or more ejectors 32 are fitted in the wall of the said container, the said ejectors consisting of nozzles 33 and 34. The suction chamber of the nozzle 33 is connected through a vertically extending passage 35 with the top end 36 of the container

16. In the example shown in the figures the said ejectors are located within the same plane as passages 26 that act as a centrifugal pump. But the construction may also be such that the ejectors are located within a plane different from that of the passages 26. The ejectors are operated by the coagulating bath which is delivered through the nozzles 33, 34 by centrifugal action.

For starting the spinning operation the apparatus is lowered so far that the head 15 is immersed with the passages 26 in the coagulating liquid contained within the receptacle 31, so that the container 16, the head 15 and also the receptacle 29 are nearly filled with coagulating bath (in Fig. 2 the level of the surface of the bath when the apparatus has been so lowered is indicated by the dotted line c, c). For the normal spinning operation the nozzle and the container 16 must be rotated from 5000 to 8000 revolutions per minute. But for starting spinning (the apparatus being in the lowered and submerged position described) this velocity is too high, and therefore means must be provided for rotating the spinning apparatus at comparatively low velocity when the operation is started. For this purpose at the beginning of the spinning operation three-phase current of lower frequency and lower voltage may be imparted to the motor 17, so that its number of revolutions is only a few hundreds per minute, the said number of revolutions being only so large that as the apparatus is raised and the passages 26 emerge from the bath the apparatus will act as a centrifugal pump for drawing the coagulating liquid through the container 16. After the flow of the coagulating liquid has thus been started the spinning apparatus is continuously moved upwardly until only the bottom end of the container 16 is immersed into the coagulating bath. Now the level of the coagulating bath is such as has been indicated by the full line b—b. Meanwhile three-phase current of the normal frequency is supplied to the motor 17, so that the number of revolutions of the device rises as far as is necessary for a normal spinning operation.

In a modification the number of revolutions of the motor is reduced by providing the stator with two windings for different numbers of revolution.

The thread guide consists of two pins 38 and 39 on which the filament delivered from the container 16 is guided before it is wound on a roller 40 transmitting the same to a collecting device. The said pins are mounted on an angular rod 41 the top part of which is disposed at an obtuse angle to the main part thereof. The said rod is guided in a vertical guide way provided on the frame 18, 19, and the said guide way is engaged either by the upper straight portion 410 of the rod, or by the lower straight portion, angularly disposed with respect to the portion 410, and to which the numeral 41 is immediately applied, the said rod being set in its positions from its top end and from above the coagulating bath.

The spinning operation is started as follows:

From the spinning apparatus the funnel shaped container 16 is removed, and the apparatus is lowered by means of the rope 24 so far that the nozzle is just immersed into the coagulating bath. The spinning liquid or viscose is supplied to the nozzle, and the filament being formed is drawn through the funnel shaped container 16 by means of a wire or hook and thereafter the said container is fixed to the head 15 by means of a nut 42. The filament is now placed on the roller 40,

and the spinning apparatus is further lowered until the spinning head and particularly the passages 26 forming the centrifugal pump are completely immersed, and the air is expelled from the container 16 (Fig. 6). The rod 41 now is in the position A, shown in Fig. 6 in dashes and dots, in which position the pins of the thread guide are located slightly below the surface a—a of the spinning bath. The bottom part of the rod is temporarily retained in such position within the guide way by means of a screw nut (not shown). The said rod is then lowered until its upper angularly disposed portion 410 engages a stop 43. Thereby the thread guide pins get into the position shown in dotted lines in Fig. 6 in dashes. Next, the rod 41 is turned counterclockwise about the stop 43, until the top part 410 engages the guide way, and the pins 38, 39 of the thread guide are in the correct position relatively to the container 16, as is shown in Fig. 6 in full lines.

Now the motor is started with low velocity, and the apparatus is raised until the bores 26 emerge from the surface of the bath, so that the centrifugal pump begins to draw the coagulating liquid upwardly and through the container 16. The spinning apparatus is then lifted so far that only the bottom end of the container is immersed into the coagulating bath, as is shown in Fig. 2, and the level of the bath relatively to the container is at b—b. Finally the length of the course of the filament within the coagulating bath 31 may be increased by moving the rod 44 from the position C into the position D (Fig. 5). Meanwhile the speed of rotation has been increased to the high velocity needed for twisting. The coagulating liquid is ejected from the spinning head 15 through the holes 26 and into the receptacle 29 (Fig. 2), and it is removed from the said receptacle through the gutter 30. The object of the jacket 27 is to confine the vapor of coagulating bath produced by the rotary movement of the container 16 and to prevent the same from spoiling the air of the workshop. The said jacket may be connected to a fan for removing the gas. The ribs 28 are fixed to the jacket 27 and they prevent transmission of the rotary movement of the container 16 to the coagulating bath.

Any gas or air which may rise within the container 16 is removed by the ejectors 33, 34.

By means of the construction shown in Fig. 7 air and gas are effectively removed from the container 16 by ejector action. Therefore the bores 26 forming the centrifugal pump are always completely filled with coagulating liquid, and therefore their efficiency is not impaired by air carried along by the coagulating liquid.

In Figs. 10 to 17 I have shown further modifications in which the air and gas are removed in a reliable way. In these modifications bevelled guide faces for the said gas and air or bubbles of gas or air are provided.

In the construction shown in Fig. 10 the spinning liquid or viscose is forced downwardly by a pump through a tubular axis 45 and into a chamber 47 formed in a head 46, and it gets from the said chamber through small bores 48 into an annular passage 49 and an annular nozzle 50. To the tubular axis 45 a cup 51 is secured to which a funnel shaped container 52 is fixed by means of a cap screw 53. The annular nozzle 50 is fixed by means of a cap screw 54 and a screw 55 to the head 46, packing rings 56, 57 and 58 being provided for affording a tight joint.

Near its top part the cup 51 is provided with 75

passages 59 and ejector nozzles 60, 61. Therefore by centrifugal action the coagulating liquid is drawn through the container 52. Air or gas bubbles which might rise within the container 5 cannot be collected on the nozzle by reason of the tapering shape of the said annular nozzle, and they rise either outwardly along the outer tapering wall of the cap screw 54, or along the inner wall of the nozzle formed by the conical bottom end of an axial bore 63 of the screw 55. Through the said bore the air or gas gets through a chamber 64 and inclined and outwardly directed passages 65 and 66 to the top part 67 of the cup 51, from whence they are drawn off by the ejectors 60, 61.

The sectional view of Fig. 11 shows the vertical bores 48 and the inclined passages 65 and 66.

The sectional view shown in Fig. 12 shows passages 59 in addition to the ejectors 60, 61 the coagulating liquid being delivered through the said passages by centrifugal action. These passages may be dispensed with in which case the coagulating liquid is delivered exclusively through the ejectors.

25 The velocity of the flow of the coagulating liquid in the bores 63, 65 and 66 and the annular top part of the container 52 above the nozzle is determined by the dimensions of the cross-sections respectively of the axial bore 63 and the 30 passage between the head 54 and the adjacent wall of the container 52. Thereby the flow within the axial bore 63 is made such that the air bubbles are safely removed without interfering with the formation of the filament from the viscose delivered through the bores of the nozzle.

35 In the modification shown in Fig. 13 the bores of the nozzle are inclined inwardly and downwardly, in accordance with the tendency of the filaments, the specific gravity of which is smaller than that of the coagulating bath, to direct themselves inwardly by centrifugal action.

40 In the modification shown in Fig. 14 the nozzle 70 is mounted on a head 69. The nozzle is formed with a downwardly directed conical extension 71 in which the bores of the nozzle are made. The air or gas bubbles which rise within the container collect near the axis of the device, because their specific gravity is smaller than that of the coagulating bath. But they cannot stick to the 45 conical nozzle 71, and they flow upwardly along the said conical nozzle and the conical outer wall of the nut 54. They are collected at the top part of the cup 51 at 67 and are removed by ejectors 60, 61.

50 In Fig. 14 the level of the coagulating liquid 55 of the bath is shown to stand higher than the discharge orifices 60, 61. From what has gone before it will be understood that this position of the apparatus in the bath is the initial position, when operation is beginning.

55 In the modification shown in Fig. 15 a nozzle of normal construction is used which has a conical body 72 axially secured thereto, for example by means of a screw, the said conical body being made for example from artificial resin.

60 In Fig. 16 an annular nozzle 73 is provided which has a conical body 74 fixed thereto by means of a cylindrical stud 75 fitted in the central part of the nozzle.

65 In the modification shown in Fig. 17 a conical body 77 is fitted axially within an annular nozzle 78, and the said nozzle is formed with an axial bore 79 communicating at its top end with the container for the coagulating liquid through inclined passages 80.

By means of the conical bodies fixed to the bottom parts of the nozzles the filaments are separated from each other so that they do not stick to one another.

Figs. 18 and 19 show a modification of the manner of suspending the spinning apparatus. The spinning apparatus is mounted on a frame composed of a pair of rails 92 having pins 81 fixed thereto, by means of which they are guided in slots 82 made in brackets 83. The rails are suspended by means of a rope 84 from a pulley 85, so that the whole apparatus may be lowered and lifted, as has been described above. The thread guides 86 are fixed to the rails 92.

For starting the spinning operation, the whole apparatus is immersed with the tubular container 87 into the coagulating bath 88, and spinning is started with low velocity of the container 87 and the nozzle mounted therein. For pulling the filament being formed from the container 87, the whole apparatus is turned into the position shown in Fig. 18 in dotted lines, so that the bottom end of the container 87 is near the surface of the bath. Thus the filament can be readily pulled from the container and passed over rollers 89 and 90 on a bobbin 91. Now the apparatus is returned into vertical position and lifted so far that only the bottom end of the container 87 is immersed into the bath.

I claim:

1. An apparatus for spinning rayon, comprising a vertically mounted rotary pipe, a spinning nozzle borne by said pipe and rotatable therewith, means for drawing filament as it is developed from said nozzle and in the line of the axis of rotation, and means for maintaining the spinning nozzle and the newly developed filament immersed in a correspondingly rotating bath of coagulating liquid, such means consisting of a receptacle for coagulating liquid and a tubular container arranged coaxially with said pipe and integrated with the pipe and rotating therewith, said container rising from beneath the surface of a body of liquid within said receptacle and enveloping the filament developed from the said spinning nozzle, and forming an annular chamber surrounding the nozzle, the said container at its lower end and beneath the surface of the liquid in the receptacle being open, and at its upper end being provided with a delivery orifice spaced from the vertical axis of the container at a distance greater than the radius of the open lower end of the container, the container being substantially closed at its upper end.

2. An apparatus for spinning rayon comprising a vertically mounted rotary pipe, a spinning nozzle borne by said pipe and rotatable therewith, means for drawing filament as it is developed from said nozzle and in the line of the axis of rotation, and means for maintaining the spinning nozzle and the newly developed filament immersed in a correspondingly rotating bath of coagulating liquid, such means consisting of a receptacle for coagulating liquid and a tubular container arranged coaxially with said pipe and integrally united with the pipe and rotating therewith, the said container rising from beneath the surface of a body of liquid within said receptacle and enveloping the filament developed from the said spinning nozzle, and forming around the nozzle an annular chamber, the said container at its lower end and beneath the surface of the liquid in the receptacle being open, and at its upper end being provided with a delivery orifice spaced from the vertical axis of the

75 container at a distance greater than the radius of the open end of the container, and a downwardly tapering conical lid formed at its center with a delivery opening, substantially closing the said container above.

3. An apparatus for spinning rayon comprising a vertically mounted rotary pipe, a spinning nozzle borne by said pipe and rotatable therewith, means for drawing filament as it is developed from said nozzle and in the line of the axis of rotation, and means for maintaining the nozzle and the newly developed filament immersed in a correspondingly rotating bath of coagulating liquid, such means consisting of a receptacle for coagulating liquid and a tubular container arranged coaxially with said pipe and rotatable therewith, the said container rising from beneath the surface of a body of liquid within said receptacle and enveloping the filament developed from the said spinning nozzle, and forming an annular chamber around the nozzle, the said container at its lower end and beneath the surface of the liquid in the receptacle being open, and at its upper end being provided with a delivery orifice spaced from the vertical axis of the container at a distance greater than the radius of the open lower end of the container, the container being substantially closed at its upper end, and a gas ejector arranged in said opening.

4. An apparatus for spinning rayon comprising a vertically mounted rotary pipe, a spinning nozzle borne by said pipe and rotatable therewith, means for drawing filament as it is developed from said nozzle and in the line of the axis of rotation, and means for maintaining the nozzle and the newly developed filament immersed in a correspondingly rotating bath of coagulating liquid, such means consisting of a receptacle for coagulating liquid and a tubular container arranged coaxially with said pipe integrated with the pipe and rotating therewith, said container rising from beneath the surface of a body of liquid within said receptacle and enveloping the filament developed from the said spinning nozzle, and forming an annular chamber around the nozzle, the said container at its lower end and beneath the surface of the liquid in the receptacle being open, and at its upper end being provided with a delivery orifice spaced from the vertical axis of the container at a distance greater than the radius of the open lower end of the container, the container being substantially closed at its upper end, and a gas ejector arranged in said opening and a gas passageway formed in the wall of the container and leading from the chamber within the container and from the highest portion thereof to the said gas ejector.

5. An apparatus for spinning rayon comprising a vertically mounted rotary pipe adapted to receive spinning liquid from above, a spinning nozzle provided with bores borne by said pipe at its lower end and rotatable therewith, the outer surface of the nozzle adjacent the opening of such bores being oblique in extent, means for drawing filament as it is developed from said nozzle downward and in the line of the axis of rotation, and means for maintaining the nozzle and the newly developed filament immersed in a correspondingly rotating bath of coagulating liquid, such means consisting of a receptacle for coagulating liquid and a tubular container arranged coaxially with said pipe in-

tegrated with the pipe and rotating therewith, the said container rising from beneath the surface of a body of liquid within said receptacle and enveloping the filament developed from the said spinning nozzle and forming an annular chamber around the nozzle, the said container at its lower end and beneath the surface of the liquid in the receptacle being open, and at its upper end and at a level higher than the opening of the bores in the spinning nozzle being penetrated with a delivery orifice, such a delivery orifice being spaced from the vertical axis of the container at a distance greater than the radius of the open lower end of the container, the container being substantially closed at its upper end.

6. An apparatus for spinning rayon comprising a vertically mounted rotary pipe adapted to receive spinning liquid from above, a spinning head borne by the said pipe at its lower end and rotatable therewith, the head being provided with downwardly directed bores grouped in annular formation, and the head being further provided with an axial passageway that opens from below with conical walls converging upwardly and that leads upward and delivers laterally through the body of the said spinning nozzle, means for drawing filament as it is developed from said head downward and in the line of the axis of rotation, and means for maintaining the spinning head and the newly developed filament immersed in a correspondingly rotating bath of coagulating liquid, such means consisting of a receptacle for coagulating liquid, and a rotary container arranged coaxially with said pipe united to and rotating in unison with the pipe, the said container rising from beneath the surface of a body of liquid within said receptacle and enveloping the filament developed from the said spinning nozzle, and forming around the head an annular chamber, the said container at its lower end and beneath the surface of the liquid in the said receptacle being open, and at its upper end and at a level higher than the opening of the bores in the head being penetrated with a delivery orifice, such delivery orifice being spaced from the vertical axis of the container at a distance greater than the radius of the open lower end of the container, the container being substantially closed at its upper end.

7. An apparatus for spinning rayon comprising a vertically mounted rotary pipe adapted to receive spinning liquid from above, a spinning nozzle borne by the said pipe at its lower end and rotatable therewith, the nozzle being provided with downwardly directed bores, and the nozzle being tapered in its central portion downwardly, means for drawing filament as it is developed from said nozzle downwardly and in the line of the axis of rotation, and means for maintaining the nozzle and the newly developed filament immersed in a correspondingly rotating bath of coagulating liquid, such means consisting of a receptacle for coagulating liquid and a tubular container arranged coaxially with said pipe united to the said pipe and rotating therewith, the said container rising from beneath the surface of a body of liquid within the said receptacle and enveloping the filament developed from the said spinning nozzle, and forming an annular chamber around the nozzle, the said container at its lower end and beneath the surface of the liquid in the receptacle being open, and at its upper end and at a level higher than the opening of the bores in the spinning nozzle being pen-

etrated with a delivery orifice, such delivery orifice being spaced from the vertical axis of the container at a distance greater than the radius of the open lower end of the container, the container being substantially closed at its upper end.

8. An apparatus for spinning rayon comprising a vertically mounted rotary pipe adapted to receive spinning liquid from above, a spinning nozzle borne by the said pipe at its lower end and rotatable therewith, the nozzle being provided with downwardly directed bores grouped in annular formation, and a downwardly tapered block fixed to the nozzle within the annulus of bores, means for drawing filament as it is developed from said nozzle downwardly and in the line of the axis of rotation, and means for maintaining the nozzle and the newly developed filament immersed in a correspondingly rotating bath of coagulating liquid, such means consisting of a receptacle for coagulating liquid and a tubular container arranged coaxially with said pipe and united integrally with the pipe and rotating therewith, the said container rising from beneath the surface of a body of liquid within the said receptacle and enveloping the filament developed from the said spinning nozzle, and forming around the nozzle an annular chamber, the said container at its lower end and beneath the surface of the liquid in the receptacle being open, and at its upper end and at a level higher than the openings of the bores in the spinning nozzle being penetrated with a delivery orifice, such delivery orifice being spaced from the vertical axis of the container at a distance greater than the radius of the open lower end of the container, the container being substantially closed at its upper end.

9. An apparatus for spinning rayon comprising a vertically mounted rotary pipe adapted to receive spinning liquid from above, a spinning head borne by the said pipe at its lower end and rotatable therewith, the head being provided with downwardly directed bores grouped in annular formation, and a block fixed centrally in the head, said block being formed with a tapering lower end, projecting downwardly from the head within the circle of its bores, and having itself an axial bore, a passageway formed in the body of the head outwardly, through which the bore in the said block has communication, means for drawing filament as it is developed from said head downwardly and in the line of the axis of rotation, and means for maintaining the nozzle and the newly developed filament immersed in a correspondingly rotating bath of coagulating liquid, such means consisting of a receptacle for coagulating liquid and a tubular container arranged coaxially with said pipe and united for integral rotation with said pipe, the said container rising from beneath the surface of a body of liquid within the said receptacle and enveloping the filament developed from the said spinning head and forming around the nozzle an annular chamber, the said container at its lower end and beneath the surface of the liquid within the receptacle being open, and at its upper end and at a level higher than the opening of the bores in the spinning head being penetrated with a delivery orifice, such delivery orifice being spaced from the vertical axis of the container at a distance greater than the radius of the open lower end of the container, the container being substantially closed at its upper end.

10. An apparatus for spinning rayon compris-

ing a vertically mounted rotary pipe, adapted to receive spinning liquid from above, a spinning nozzle borne by said pipe at its lower end and rotatable therewith, means for drawing filament as it is developed from said nozzle downward and in the line of the axis of rotation, means for maintaining the spinning nozzle and the newly developed filament immersed in a correspondingly rotating bath of coagulating liquid, such means consisting of a receptacle for coagulating liquid and a tubular container arranged coaxially with said pipe and united with the said pipe and rotatable therewith, said container adapted to occupy a position in which it rises from beneath the surface of a body of liquid within the receptacle, enveloping the filament developed from the said spinning nozzle and forming an annular chamber around the spinning nozzle, the said container at its lower end and beneath the surface of the liquid in the receptacle being open, and at its upper end being provided with a delivery orifice spaced from the vertical axis of the container at a distance greater than the radius of the open lower end of the container, the container being substantially closed at its upper end, means for raising and lowering the container relatively to the level of the liquid in the receptacle, and a thread guide movable with the container as it is raised and lowered.

11. In combination with a receptacle for coagulating liquid, apparatus for spinning rayon consisting of a vertically mounted rotary pipe adapted to receive spinning liquid from above, a spinning nozzle borne by said pipe at its lower end and rotatable therewith, means for drawing filament as it is developed from said nozzle downward and in the line of the axis of rotation, means for maintaining the nozzle and the newly developed filament immersed in a correspondingly rotating bath of coagulating liquid, such means consisting of a tubular container arranged coaxially with said pipe, united with the pipe, and rotatable therewith, said container adapted to occupy a position in which it rises from beneath the surface of a body of liquid within said receptacle as it is raised and lowered.

tacle, enveloping the nozzle and forming an annular chamber around the nozzle, the said container at its lower end and beneath the surface of the liquid in the receptacle being open, and at its upper end being provided with a delivery orifice spaced from the vertical axis of the container at a distance greater than the radius of the open lower end of the container, the container being substantially closed at its upper end, a thread guide carried on a rod including two portions angularly disposed relatively to each other, and a guide-way borne by the spinning apparatus with which the said rod in either of its portions may be engaged.

15 12. An apparatus for spinning rayon, comprising
a vertically mounted rotary pipe, a spinning
nozzle borne by said pipe and rotatable therewith,
means for drawing filament as it is developed
from said nozzle and in the line of the axis of ro-
tation, means for maintaining the spinning nozzle
and the newly developed filament immersed in a correspondingly rotating bath of coagulating
liquid, such means consisting of a receptacle for
the coagulating liquid and a tubular container
20 arranged co-axially with said pipe and integrated
with the pipe and rotating therewith, said container
rising from beneath the surface of a body
of liquid within said receptacle and enveloping
the said spinning nozzle and filament developed
therefrom, and forming an annular chamber sur-
rounding the nozzle, the said container at its
lower end and beneath the surface of the liquid
30 in the receptacle being open and at its upper
end being provided with a delivery orifice spaced
from the vertical axis of the container at a dis-
tance greater than the radius of the open lower
end of the container, the container being sub-
stantially closed at its upper end, and a jacket
35 surrounding the container and immersed in the
coagulating bath, the jacket being provided with
ribs that constitute braking members adapted
40 to check induced rotation of the liquid in the re-
ceptacle.
